(57) **CLAIM**

The ornamental design for a chair, as shown and described.

DESCRIPTION

FIG. 1 shows a perspective view of my design for a chair; FIG. 2 shows a side view thereof, with the opposite side being a mirror image thereof;

FIG. 3 shows a top view thereof;

FIG. 4 shows a rear view thereof; and,

FIG. 5 shows a front view thereof.

The bottom view forms no part of the design.

The dotted pattern shown on the seat and backrest represents fabric material.
